UNITED STATES PATENT OFFICE.

ERIK L. KRAM, OF CHICAGO, ILLINOIS.

LOCK-BOX.

SPECIFICATION forming part of Letters Patent No. 746,106, dated December 8, 1903.

Application filed January 21, 1903. Serial No. 140,028. (No model.)

To all whom it may concern:

Be it known that I, ERIK L. KRAM, a citizen of the United States, residing at Chicago, in the county of Cook and State of Illinois, have 5 invented certain new and useful Improvements in Lock-Boxes, of which the following is a specification.

One of the objects of this invention is the production of a lock-box having a protected 10 hinge for its door or cover.

A further object of the invention is the improvement in details and the general arrangement of parts hereinafter more fully set forth. In the accompanying drawings, Figure 1 is 15 a horizontal section through a lock-box embodying my invention, taken on dotted line 1 1 of Fig. 2. Fig. 2 is a vertical section on dotted line 2 2 of Fig. 1. Fig. 3 is a horizontal section showing a modified construction.

20 In the construction of this lock-box I provide a receptacle comprising the top 1, the bottom 2, the rear wall 3, the side walls 4 and 5, and the door 6. The forward edge of the side wall 4 is bent over toward said door at 25 right angles with the main portion of said wall in the covering-flange 7. An angle-iron bracket 8, having an integral side flange 9, is secured to the side wall 4 near the forward edge thereof by means of rivets 10 passing 30 through suitable openings (not shown) in said side wall 4 and said flange 9. Hinges 11, of ordinary construction, are secured to the angle-iron bracket 8 and the inner side of the door 6, whereby said door is pivotally mounted 35 with relation to said box. The door fits tightly within the forward edges of the top, bottom, and side walls of the receptacle, inward movement being limited by the rear edge of said door striking against the inner 40 side of the covering-flange 7. The door may be swung freely outward upon its hinge-joint into the position indicated by dotted lines in Fig. 1.

In the modified form illustrated in Fig. 3 the flange 7 is omitted. 45

It is apparent that lock-boxes embodying my invention might be made with a single separating-wall between them, that separate angle-iron brackets might be used to support each of the hinges 11, and that many other 50 and further changes might be made in the construction of this lock-box and the arrangement of its parts without departing from the spirit and scope of my invention. Therefore I desire to have it understood that I do 55 not limit myself to the precise form or arrangement of parts herein shown and described.

I claim as my invention—

1. In a lock-box, in combination, a receptacle having an open side; a closure for said open side; a bracket secured within the receptacle, near the open side thereof; and a hinge connection between said bracket and the inner side of said closure. 60 65

2. In a lock-box, in combination, a receptacle having an open side; a closure for said open side; an angle-iron bracket having a longitudinal flange at one side thereof, which angle-iron bracket is secured to said receptacle near the open side thereof; and a hinge connection between said bracket and the inner side of said closure. 70

3. In a lock-box, in combination, a receptacle having an open side, one of its sides being provided with an inturned covering-flange partially closing the open side; a closure for said open side; a bracket formed of angle-iron and secured within the receptacle adjacent to the covering-flange; and a hinge connection between said bracket and the inner side of said closure. 75 80

ERIK L. KRAM.
